CLOCK OR SIMILAR ARTICLE

Walter C. Anderson, Southport, Conn., assignor to General Electric Company, a corporation of New York

Filed Mar. 13, 1964, Ser. No. 78,986

Term of patent 3½ years

(Cl. D42—7)

Fig. 2.

Fig. 1.

Fig. 4.

Fig. 3.

FIG. 1 is a front perspective view of a clock embodying my new design;

FIG. 2 is a front elevational view of the clock shown in FIG. 1;

FIG. 3 is a side elevational view of the clock shown in FIG. 1; and

FIG. 4 is a rear elevational view of the clock shown in FIG. 1.

The essential features of my design are shown in full lines in the drawing.

I claim:

The ornamental design for a clock or similar article, substantially as shown and described.
